UNITED STATES PATENT OFFICE.

WALTER S. STROWGER, OF ROCHESTER, NEW YORK, ASSIGNOR TO
HENRY H. PRYOR, OF ROCHESTER, NEW YORK.

RAILWAY-TRACK.

No. 826,201.

Specification of Letters Patent.

Patented July 17, 1906.

Application filed August 4, 1904. Serial No. 219,487.

To all whom it may concern:

Be it known that I, WALTER S. STROWGER, a citizen of the United States, and a resident of Rochester, in the county of Monroe and 5 State of New York, have invented certain new and useful Improvements in Railway-Tracks, of which the following is a specification.

This invention relates to railway-tracks; 10 and it consists in the mechanism hereinafter described and claimed.

In the drawings, Figure 1 is a perspective view of a metal tie adapted for use in connection with this invention. Fig. 2 is a cross-15 section through a portion of the tie, showing the rails in place; and Fig. 3 is a view of a tie of a slightly-modified form.

Railway-tracks need to be so embedded in the ground or in ballast or other foundation 20 as to be incapable of longitudinal or lateral movement, and of the two movements the lateral movement is the more detrimental. Further, the use of metal for ties is desirable on account of its cheapness, rigidity, and 25 permanency.

In the drawings, Fig. 1 shows a metal tie adapted to support rails and to maintain them in place in the desired position upon the road-bed. The tie consists of a bar of metal 30 1, having two folds 2 projecting downwardly therefrom and having the groove 3 between the folds transverse to the body 1. At right angles to these folds and along one or both edges of the body 1 are downwardly-35 turned flanges 4 and 5, the flanges 4 being turned down from the edges of that portion of the tie between the folds 2 and the flanges 5 being turned down from the side edges of the end portions 6 of the tie outside of the 40 folds 2. In the form of tie shown in Fig. 1 the edges from which the flanges are turned down are in straight lines; but in Fig. 3 these edges are curved lines, as shown at 7 and 8, whereby the tie may be made of a piece of 45 sheet metal, say, three-eighths or one-half inch in thickness, with parallel edges, and then the flanges 9 and 10 are turned down from these parallel edges by stretching the metal, substantially as shown in said Fig. 3. 50 In the cavity or groove 3 in the interior of the

flange 2 is set a flangeless rail, which has a vertical web 11, that fits in the groove 3 and extends from tie to tie and into the ground between the ties. Upon the top of the web 11 is the head 12 of the usual form of rails. 55 The web 11 of the rail is in many instances bolted in the groove 3 by a suitable bolt 13, passing through the two walls of the fold 2 and through the web 11, thus fastening the parts together. In some instances, however, 60 this mode of bolting appears to be unnecessary. The bolt-holes 14, Fig. 1, are drilled through the two sides of the fold 2 in those ties where the bolting is desirable. The deep fold 2 and the flanges 4 and 5 at right angles 65 to said folds rest in the ballast, ground, or foundation for the railway-track and prevent either longitudinal or lateral movement of the ties, thus maintaining the rails in proper position, and the webs 11 of the rails between 70 the ties also tend to maintain the rails in proper position longitudinally by means of the large surface which would have to be forced laterally through the ground, ballast, or other foundation. In Figs. 1 and 2 also 75 the flanges 4 and 5 of the tie are shown integral with the edges of the folds 2, as stated above, and are turned down between said folds from the bottom of each fold in each direction. In this way the maximum staying 80 of the folds is produced.

What I claim is—

1. A railway-track consisting of a series of ties having registering transverse grooves provided with walls, a series of flangeless 85 rails each consisting of the usual head and a vertical web set in the grooves of the series of ties, and bolts passing through the walls of said grooves and through said web.

2. A railway-track consisting of a series of 90 ties having registering transverse grooves provided with walls, a series of flangeless rails each consisting of the usual head and an integral, vertical web set in the grooves of the series of ties, and bolts passing through the 95 walls of said grooves and through said web.

3. A railway-track consisting of a series of ties having folds therein transverse to the tie, a flange longitudinal to the tie, and a series of 100 rails, each consisting of the usual head and a

vertical flange resting in the grooves formed by the folds of the series of ties.

4. A railway-track consisting of a series of ties having folds therein transverse to the tie, and flanges longitudinal to the tie, and a series of rails each consisting of the usual head and an integral vertical flange resting in the

grooves formed by the folds of the series of ties.
